FURNACE WALL

Oscar Nygaard, Saugus, Mass.

Application December 18, 1931, Serial No. 581,807

17 Claims. (Cl. 72—101)

This invention relates to furnace walls and is more especially concerned with that type of wall in which a structural steel frame is used to carry a considerable part, or all, of the weight of the wall.

It is the chief object of the invention to improve furnace walls of the structural steel supported type with a view to reducing the weight of metal required in the wall, facilitating the erection and repair of such walls, and devising a construction which can readily be adapted to the requirements of different installations.

The nature of the invention will be readily understood from the following description when read in connection with the accompanying drawings, and the novel features will be particularly pointed out in the appended claims.

In the drawings,

Figure 1 is a front elevation of a small section of a furnace wall constructed in accordance with this invention, illustrating the wall in the process of erection;

Fig. 2 is a vertical, sectional view of the structure shown in Fig. 1;

Fig. 3 is a perspective view of one of the brackets used in the wall illustrated in Figs. 1 and 2, and shows also the manner in which the horizontal bars may be assembled with or removed from the bracket;

Fig. 4 is a horizontal sectional view of a portion of the wall shown in Fig. 1;

Fig. 5 is a vertical, sectional view illustrating a construction which may be used at the top of the wall;

Fig. 6 is a plan view of one of the bottom bars for connecting the members of an adjacent pair of brackets; and

Fig. 7 is a front view of the parts shown in Fig. 6.

Referring more especially to Figs. 2 and 3 it will be seen that the wall structure there shown comprises an inner or front wall section A, an outer or rear wall section B, and an intermediate air space C which separates said front and rear sections A and B. The front section or facing of the wall is exposed to the fire and forms one wall of the combustion chamber.

The rear wall section B includes a structural steel frame which comprises upright posts 2 and horizontal beams 3 bolted or riveted to the posts 2, both of these structural steel members being of channel or I section, as desired. This rear section as shown also includes a brick wall 4 which is supported on the horizontal beams 3

and an insulating section 5 behind the wall 4 and backed up by a sheet metal shell or casing 6.

It is contemplated that the rear section B will be relatively permanent since it is protected from the disintegrating action of the high temperature gases in the combustion chamber, but that the lining which is subjected to the action of said gases will require repair or renewal from time to time. This lining is composed chiefly of bricks or blocks 7 which may be made of fire clay or any other suitable refractory material. In order to facilitate the replacement or repair of this section of the wall without disturbing the rear wall section B, the front section is constructed in panels which are relatively independent of each other and each panel is arranged to be supported by a pair of brackets 8.

Referring more especially to Figs. 2 and 3 it will be seen that each bracket includes an upright elongated beam section a and a relatively heavy arm b which extends rearwardly from an intermediate point in the length of the beam section a and is hooked on to one of the horizontal bars 3. A row of these brackets is mounted on each beam 3 and the beam sections a of each row are located substantially in vertical alignment with each other. Each bracket thus can swing about the edge of the beam 3 over which it is hooked, and in order to facilitate the initial adjustment of the brackets into alignment with each other the enlarged or rest portion c of the bracket in which the slot d is formed to receive the edge of the flange is provided near its lower edge with two bolts 10 positioned to bear against the lower part of the flange of the beam 3. By turning these bolts inwardly the bracket 8 may be swung in a clockwise direction, Fig. 2, about the edge of the beam flange on which it rests, so that it can readily be brought into initial alignment with the other brackets. Each bracket is held in its aligned position by blocks or bricks 12, Fig. 2, resting partly on the foot e on the lower end of the bracket and partly on an angle iron member 13, Fig. 2, which is bolted or riveted to the upright posts 2 and which may be made of any suitable length.

Considering any two adjacent brackets in horizontal alignment with each other as forming a pair, it will be observed that the lower ends of the brackets are connected together by a bar 14. The opposite ends of this bar rest on the foot portions e of the two brackets and are bolted loosely to them, as best shown in Fig. 6, one of the bolts passing through a slot in the end of the bar 14 so

that some relative movement of the brackets toward and from each other due to expansion and contraction is permitted. This bar 14 supports the entire weight of all of the blocks in one panel 5 and it is so designed as to be very stiff, strong and rigid, having somewhat the construction of a truss, as shown in Figs. 2, 6 and 7. The lowermost row of blocks in a panel rests directly on one of these bars 14, all of these blocks or bricks being 10 grooved on their lower side, as indicated in 15, Fig. 2, to receive a flange or rib 16 which projects from the upper side of the bar 14.

Additional courses of blocks 7 laid one on the other are included in each panel and these rows 15 are held in alinement with the bottom row and with each other by means of bars 17 of T-shape sectional form, as clearly shown in Figs. 2 and 3, the opposite ends of each bar resting in slots or sockets *f* formed in opposite sides of the beam 20 section *a* of the two adjacent brackets 8. In the particular construction shown there are three of these sockets in each side of each beam section *a* and the sockets on one side lie directly opposite and in alinement with the respective sockets on 25 the opposite side. Consequently, in laying up any individual panel after the lowermost course of blocks 7 has been placed in position, a bar 17 is next laid horizontally on top of this lowermost course with the middle flange of the bar lying 30 horizontally and the end flange vertically. The latter flange enters the grooves 15' in the upper edges of the courses of blocks already laid. The second course of blocks is then placed in position, after which another bar 17 is placed on them, in 35 the manner above described, with its ends located in the slots *f*—*f* of the two brackets, these operations being repeated until the entire panel is completed, with the exception of the course of key blocks or filler blocks 18. This horizontal course 40 of key blocks is placed in position after all the others have been located and a yielding packing 20 of asbestos, magnesia, or some other suitable material, then is driven into the relatively narrow space surrounding each panel and separating 45 it from the next adjacent panel. The key bricks are held in place simply by their tongue and grooved connection with the uppermost course of blocks 7 and by the presence of the packing joint immediately above them. The packing yields 50 sufficiently to allow each panel to expand and contract with changes in temperature. At the same time it protects the structural metal members 14 and 8 which lie immediately behind the packing joints, as will be evident from an inspection 55 of Fig. 4. These packings also prevent any substantial flow of air or gases through the front section or lining *a* of the wall between adjacent panels. This is an important advantage when air is circulated through the space *c* for the purpose of cooling the lining, preheating the air, or 60 for any other reason.

When it becomes necessary to repair any section of the furnace lining or facing, or to replace a broken brick in any section of the facing, it is 65 simply necessary to dig out the packing 20 above the row of key bricks 18 for that section, then to withdraw these bricks and remove enough of the blocks 7 in that particular panel to permit access to the broken block or to the region which 70 must be repaired. When the broken block has been replaced or the other repairs completed, the rest of the panel may then be built up by following the same procedure used in installing the panel initially.

75 At the upper edge of the refractory section of

the wall a masonry section may be built in any one of several ways. For example, a wide channel 22, Fig. 2, may be secured to the posts 2, this channel being used to support the masonry wall above the refractory section and independent of it.

80 A slightly different arrangement is shown in Fig. 5 in which the bracket 8' is like the bracket 8 except that it is cut off just above the level of the upper pair of slots *f*, and a T-bar 23 is supported in these slots. A cap plate 24 rests on these T-bars and on an angle bar 25 which is bolted or riveted to the posts 2', and supports the masonry section 26 of the wall. This cap plate 24 may be 85 made in sections and it may also be used to assist in holding each bracket 8' in its upright position. As shown in Fig. 5 it is provided at one edge with a flange 27 to hook over the angle bar 25 and at its opposite edge with lugs 28 to hook over the upper end of the bracket 8'.

90 In some cases it is desirable to build a horizontal baffles in the wall between the front and rear sections. This may be done either by locating rows of bricks 12 on the bars 13 and 14, as shown in Fig. 2, or a metal baffle 30, Fig. 5, may be provided for this purpose, the edges of this baffle resting on the bars 13 and 14, while lugs 31 welded to it bear against the edges of the plates 13 and 14 and cooperate with these parts to hold the brackets 8 in their upright positions. This baffling may be 100 made to suit the requirements of any individual installation.

105 It will now be evident that this invention provides a construction in which a relatively low ratio is possible between the weight of the structural metal parts and the area of the refractory surface exposed at the fire face of the wall. The nature of the construction is such that relatively few special parts are required for any ordinary installation. In this construction also each horizontal row of panels may be placed independently 110 of the positions of the next adjacent row, thus avoiding an objection which has been found to exist with some prior constructions. In other words, the panels may either be staggered or 115 made to register with those above or below them, as desired.

120 While I have herein shown and described a typical embodiment of my invention, it will be understood that the invention may be embodied 125 in other forms without departing from the spirit or scope thereof.

Having thus described my invention, what I desire to claim as new is:

1. In a furnace wall, the combination of a 130 structural steel frame at the back of the wall, said frame including horizontal supporting members, a plurality of brackets mounted on said members and held in a substantially upright plane, each of said brackets including an elongated upright 135 member at the forward part thereof and an arm projecting rearwardly from an intermediate point in the length of said member and releasably mounted on one of the supporting members in said steel frame, bars fastened to the lower 140 portions of and connecting the members of each pair of adjacent brackets, said bars serving to hold said brackets spaced apart but permitting a slight relative movement of said brackets toward and from each other, additional bars located one above the other between each pair of adjacent brackets, said additional bars being supported on and connecting said brackets, and refractory blocks in the front section of said wall 145 engaging said bars and held by the bars in aline- 150

ment with each other at the fire side of said wall.

2. A furnace wall structure according to preceding claim 1 including means independent of said brackets and frame but cooperating with them to support said brackets against tipping movement.

3. In a furnace wall having front and rear wall sections, the combination of a structural steel frame in said rear section, said frame including 10 horizontal beams, a plurality of brackets mounted on said frame substantially in horizontal alignment with each other, each of said brackets including an approximately upright elongated member and an arm extending rearwardly from 15 an intermediate point in the length of said member and supported on one of said beams, a bottom horizontal bar connecting each pair of adjacent brackets and secured to them near their lower ends, additional horizontal bars connecting each 20 pair of adjacent brackets and located parallel to said bottom bar and spaced vertically from it and from each other, a course of refractory blocks resting on said bottom bar, and additional courses of refractory blocks located above said first mentioned course and held in alignment with each other and with said bottom course by their engagement with said additional bars.

4. A bracket for furnace wall construction comprising a beam having a supporting arm extending therefrom at an intermediate point in the length of said beam, and sockets formed in the opposite sides of said beam and each adapted to support one end of a bar.

5. A bracket for furnace wall construction comprising a beam having a supporting arm extending therefrom at an intermediate point in the length of said beam, a laterally extending foot on the lower end of said beam, and a plurality of sockets formed in said beam at each side thereof, the sockets at one side of said beam being approximately in line, respectively, with those on the other side thereof.

6. A bracket for furnace wall construction comprising a beam having a supporting arm extending therefrom at an intermediate point in the length of said beam, said arm having a thickened and slotted part forming a hook, and a plurality of sockets formed in said beam at each side thereof, the sockets at one side of said beam being approximately in line, respectively, with those on the other side thereof.

7. A bracket for furnace wall construction comprising a beam having a supporting arm extending rearwardly therefrom, said arm having a thickened and slotted part forming a hook to engage the flange of a supporting beam, and a bolt threaded through said thickened part to bear against said beam.

8. In a furnace wall, the combination of a structural steel frame for the back of the wall, a plurality of brackets mounted on said frame and held in a substantially upright plane, each of said brackets including an elongated upright member at the forward part thereof and an arm 60 projecting rearwardly from said member and releasably mounted on said frame, a plurality of horizontal bars supported on and connecting the members of each pair of adjacent brackets, the wall facing including refractory blocks located at 65 the fire side of the wall and held in alignment with each other by their engagement with said bars, additional horizontal bars connecting the upper ends of said brackets, and a cap plate connecting said bars and said frame and supported 70 on them.

9. In a furnace wall comprising front and rear wall sections with an air space between them, the combination of a structural steel frame in said rear section, said frame including horizontal beams arranged one above another and spaced apart, a plurality of brackets supported on said beams, each of said brackets including an upright elongated portion located in the front wall section and an arm extending rearwardly from an intermediate point in said elongated portion and projecting across said air space and removably mounted on one of said horizontal beams, horizontal bars connecting adjacent brackets and mounted on them, and refractory blocks located in said front wall section, at the fire side of the wall and held in place by said bars.

10. In a furnace wall comprising front and rear wall sections with an air space between them, the combination of a structural steel frame in said rear section, said frame including horizontal beams arranged one above another and spaced apart, a plurality of brackets supported on said beams, each of said brackets including an upright elongated portion located in the front wall section and an arm extending rearwardly from an intermediate point in said elongated portion and projecting across said air space and removably mounted on one of said horizontal beams, said brackets being arranged in horizontal rows in which the individual brackets are spaced apart, one of said rows being above another and the brackets in the lower rows being positioned directly under those in the upper rows, horizontal bars supported on and connecting adjacent brackets, and refractory blocks located in said front wall section at the fire side of the wall and held in place by said bars.

11. A furnace wall comprising front and rear wall sections, said front section including a plurality of panels located closely adjacent to each other in approximately adjoining relationship and each including a horizontal course of refractory bricks, horizontal bars for holding said courses of bricks in alignment in said wall, brackets spaced apart horizontally and on which said bars are mounted for expansion and contraction relatively to the brackets, the bricks in said courses being disengageable from their respective bars by an upward movement, courses of key bricks cooperating, respectively, with the previously mentioned courses of bricks to lock the latter bricks against disengagement from their respective bars, said key bricks being readily removable from the wall at the fire side thereof to permit the removal of the other bricks from said wall at said fire side without disturbing the rear wall section, a structural steel frame in said rear wall section on which said brackets are releasably supported, and means additional to said brackets for holding the portions of said brackets which support said bars spaced from said rear wall section.

12. A furnace wall comprising front and rear wall sections, said front section including a plurality of panels located closely adjacent to each other in approximately adjoining relationship and each including a horizontal course of refractory bricks, horizontal bars for holding said courses of bricks in alignment in said wall, brackets spaced apart horizontally and on which said bars are mounted for expansion and contraction relatively to the brackets, the bricks in said courses being disengageable from their respective bars by an upward movement, courses of key bricks cooperating, respectively, with the previous-

ously mentioned courses of bricks to lock the latter bricks against disengagement from their respective bars, expansion joints separating adjacent panels from each other while permitting expansion and contraction of the panels both vertically and horizontally with reference to each other, said expansion joints including means for preventing any substantial flow of gasses from the combustion chamber through said front section at points between adjacent panels, a structural steel frame in said rear wall section on which said brackets are removably mounted, and means additional to said brackets for holding the portions of said brackets which support said bars spaced from said rear wall section.

13. In a furnace wall, the combination of an upwardly extending bracket comprising an elongated front section and a supporting arm extending rearwardly therefrom at an intermediate point in the length of said front section, a support for said arm, and screw threaded means for adjusting the angular tilt of said bracket with reference to said support.

14. In a furnace wall, the combination of a refractory brick facing, a structural steel frame at the rear of said facing, said frame including horizontally extending beam sections, and brackets for supporting the elements of said refractory facing in alinement in the wall, said brackets having parts resting on and supported by said beam section and also having means for adjusting their tilt or angle relatively to said frame.

15. In a furnace wall, the combination of a refractory brick facing, a structural steel frame at the rear of said facing, said frame including

horizontally extending beam sections, brackets for supporting the elements of said refractory facing in alinement in the wall, said brackets having parts resting on and supported by said beam sections, and means for holding said brackets in different angular relationships to said frame.

16. In a furnace wall, the combination of a refractory brick facing, a structural steel frame at the rear of said facing, said frame including horizontally extending beam sections, and brackets for supporting the elements of said refractory facing in alinement in the wall, each of said brackets comprising a substantially upright elongated section in alinement with said facing and a rearwardly extending arm located at an intermediate point in the length of said elongated section and supported on one of said horizontally extending beams.

17. In a furnace wall, the combination of a structural steel frame at the back of the wall including horizontal beam sections, a plurality of brackets mounted on said frame and held in a substantially upright plane, each of said brackets including an elongated substantially upright member at the forward part thereof and an arm projecting rearwardly from an intermediate point in the length of said member and mounted on one of said beam sections, a plurality of horizontal bars supported on and connecting the members of each pair of adjacent brackets, and a wall facing including refractory blocks located at the fire side of the wall and held in alinement with each other by their engagement with said bars.
